F. SHORT

DIRIGIBLE BALLOON

Filed Jan. 25, 1924

UNITED STATES PATENT OFFICE.

FRANK SHORT, OF PENN YAN, NEW YORK.

DIRIGIBLE BALLOON.

Application filed January 25, 1924. Serial No. 688,449.

This invention relates to dirigible balloons, the broad object in view being to produce an airship of the class referred to combining certain advantageous features of the rigid and the non-rigid type, also including additional features of novelty and utility.

Among the important features of the invention, the following may be enumerated. A rigid tractor head; non-rigid tail section; 10 interchangeable intermediate flexible load sections; interconnecting adjustable tension cables; nose or head section rudders and elevators; diagonal stabilizing fins; overlapping streamlining fabric at the joints between the sections; tubular car sections with 15 internal pressure, and flexible passages or vestibules between the car sections.

A further object of the invention is to so combine the important features above enumerated as to produce a dirigible balloon of high efficiency, one in which the useful load may be made to correspond with the requirements or load carrying capacity from time to time, and one in which such change 25 in carrying capacity may be quickly adjusted without permanently discarding any part of the equipment.

With the above and other objects in view, the invention consists in the novel construction, combination and arrangement herein fully described, shown and claimed in the accompanying drawings.

Fig. 1 is a vertical diametrical section through the forward end of aerostat of the improved dirigible balloon.

Fig. 2 is a front elevation of the same.

Fig. 3 is a vertical transverse section on the line 3—3 of Fig. 1.

Fig. 4 is a vertical transverse section on line 4—4 of Fig. 1.

Fig. 5 is a rear end elevation of the dirigible balloon.

The aerostat of the improved dirigible balloon is made in sections, comprising a rigid tractor head section designated generally at A, a non-rigid tail section B, and one or more intermediate flexible or non-rigid load carrying sections C.

The head section A embodies a rigid frame shown as consisting of a suitable number of box girder longérons or frame members 10 of lattice work or other light strong construction, the shape of said longé-

rons or frame members being such as to produce in the finished aerostat a half round or streamline nose as shown. The head section also embodies transverse frame members 11, which are also shown of box girder lattice work construction, extending from the center or longitudinal axis of the aerostat radially outward where they are permanently united in any suitable way to the longérons 10. The frame further comprises one or more annular frame members or lattice work hoops 12, which interconnect and brace the radial frame members 11 as shown in Fig. 3. The head section has a covering 13 of fabric, which may be fluid tight if desired, while the rear end of the head section is closed by an inwardly extending conical 70 wall 14 of fabric, which may also be fluid tight if desired. Gas bags 14' are placed in the head section as shown in Fig. 3.

The head section A also comprises hollow fins or fixed stabilizing surfaces 15, which are properly streamlined in a fore and aft direction, and which form housings for a portion of the propelling mechanism of the dirigible. As shown the fins 15 contain the propeller shafts 16, which carry the tractor propellers or air screws 17, shown in Fig. 2. Any suitable prime mover or power plant may be placed in the head section and suitably geared for driving the tractor screws 17. Vertical rudders 18 and elevators 19 are carried by the head section A and controlled by suitable connections (not shown).

Each of the flexible or non-rigid load sections is cylindrical in shape, corresponding in diameter with the largest diameter of the head section A so as to give a streamline contour to the whole aerostat as clearly indicated in Fig. 1. Each of the load sections C has a conical forward end wall 20 and inwardly extending conical wall 21 at the rear end thereof, the front and rear walls 20 and 21 of the several load sections C being adapted to closely fit each other, and the head section and the tail section having corresponding walls to produce an interfitting connection and bracing between all of the sections of the aerostat.

The head section A is formed with a central tube or passage way 22 and each of the intermediate sections C, as well as the tail

section B, is likewise provided with a central tube or passage way 22, said tubes or passage ways being in longitudinal alinement and forming a tubular passage way extending through all of the sections of the aerostat, with the exception of the rear portion of the tail sections.

The several sections of the aerostat are held in the relation shown by means of flexible cables 23. One of such cables extends from each of the sections A, B and C through the tubular passage way 22, said cables being held under tension by winding drums 24 supported firmly in the head section A and preferably by means of brackets or the equivalent thereof, supported in turn by the frame of the head section. The sections C embody the gas compartments or spaces 25 and each of the intermediate sections C contains a balloonet 26 with suitable valves and equipment. The tail section B also embodies gas spaces or compartments 27 containing balloonets 28.

The head section has at the rear end thereof a strong annular inflated cushioning bag 29 fastened to the frame of the head section and forming a resilient abutment against which bears the front wall 20 of the next adjacent load section C as clearly shown in Fig. 1. By means of the construction described the flexible load sections are all flexibly connected together and to the head section so as to allow for the necessary weaving of the aerostat under side wind pressure and steering operations.

Arranged beneath the aerostat and suspended therefrom or supported thereby is a car which comprises longitudinally alined car sections 30 and 31. It will be observed that there is a car section for each section of the aerostat, such section being located immediately under the respective aerostat section and being connected thereto and supported thereby by means of fabric suspension members 32, which diverge from the car sections upwardly to the aerostat as shown in the cross sectional views. The car sections 30 and 31 are connected by flexible passages or vestibules 33 so as to provide for the necessary weaving of the airship. The rear section 31 of the car is joined to the next forward car section 30 by the means of a semi-rigid joint 34 and between said sections 31 and 30 there is provided an air lock indicated at 35 which may consist of two partitions having air-tight doors therein and an intervening space or vestibule. The forward cross sections numbered 30 all contain atmospheric pressure or at least pressure comfortable for the passengers to breathe. The rear section 31 will ordinarily contain air at normal pressure. The pressure in the car sections serves to inflate the same so that they assume cylindrical form.

The rear car section is internally braced

by lattice work construction 36 to which are attached upright extensions 37 and 38 which may pass upwardly through the tail end portion of the rear section B of the aerostat and support fixed stabilizing surfaces or vertical fins 39 and horizontal fins 40. Fabric webs 41 extend from the frame 36, 38 divergently upward as shown in Fig. 5 and are secured to the covering of the aerostat bearing a tangential relation thereto as shown in Fig. 5.

In order to preserve the streamline contour of the entire aerostat, overlapping fabric flaps 42 are connected to the peripheries of the sections A and C, extending across the gaps across the sections and secured by elastic means 43 to the adjoining section.

A vertical passage way 44 extends from the bottom of the tail section upwardly and intersects the tubular passage way 22 and contains a ladder, to enable the crew to obtain access to the passageway 22 for any purpose needed. The passage way 22, which is preferably formed of fabric, may be supported by the cables 23 or by webbing braces 45 as indicated in Fig. 4 or by any other suitable means so as to preserve the shape of the sections of the aerostat and provide the necessary flexibility to allow for the weaving motion of the airship.

From the foregoing description taken in connection with the accompanying drawings it will now be observed that the tractor head section is self-supporting or sustaining and the fabric or covering thereof is not required to take the drag of succeeding sections to increase the useful load of the airship to correspond with the need from time to time. It means that the head, intermediate and tail sections can be standardized and interchangeable. Therefore a damaged section may be quickly replaced by a new section instead of tying up the whole bag unit. Normally the capacity may be quickly adjusted to the traffic demand without discarding old equipment because it lacks load carrying capacity.

The tail section will normally contain such equipment as ballast, reserve fuel, reserve gas, baggage and dining compartment, crew's quarters, radio apparatus, air compressors, etc. The rear section may also have an engine driven electric generator to supply energy to some of the head section air screws as well as lighting and cooking energy.

I claim:—

1. In a dirigible balloon, an aerostat comprising a rigid head section, a non-rigid tail section, flexible intermediate load sections, and tension cable means extending along the longitudinal axis of the aerostat and flexibly tying the sections thereof together.

2. In a dirigible balloon, an aerostat comprising a rigid head section, an annular

- cushion bag carried by the rear part of said head section, interchangeable load sections trailing behind the head sections, and flexible cable means serving to tie all of the sections together. 3. In a dirigible balloon, an aerostat comprising a rigid head section, interchangeable load sections trailing behind the head section and having interfitting front and rear portions, a flexible cable means extending centrally of the sections and longitudinally of the aerostat and serving to flexibly tie the sections together. 4. In a dirigible balloon, an aerostat comprising a rigid head section, vertical rudders and elevators mounted on the head section, interchangeable load sections trailing behind the head section and having interfitting front and rear portions, a flexible cable means extending centrally of the sections and longitudinally of the aerostat and serving to flexibly tie the sections together. 5. In a dirigible balloon, an aerostat comprising a rigid head section, interchangeable flexible load sections trailing behind and flexibly tied to the head section, streamlined stabilizing fins projecting outward from the head section, and propelling means partially housed within said fins. 6. In a dirigible balloon, an aerostat comprising a rigid head section, interchangeable flexible load sections trailing behind and flexibly tied to the head section, radially extending internal bracing frame members in the head section, streamlined stabilizing fins projecting radially outward from the head section and supported by said bracing frame members, and propelling means partially housed within said fins. 7. In a dirigible balloon, an aerostat comprising a rigid head section having box girder longérons, and also having internal transverse frame members extending radially from the longitudinal axis of the head section outwardly and united to said longérons, streamlined stabilizing fins projecting radially outward from the head section and anchored to said transverse frame members, and propelling means partially housed within said fins. 8. In a dirigible balloon, an aerostat comprising a rigid head section having box girder longérons, and also having internal transverse frame members extending radially from the longitudinal axis of the head section outwardly and united to said longérons, interchangeable flexible load sections trailing behind the head section and flexibly tied thereto, streamlined stabilizing fins projecting radially outward from the head section and anchored to said transverse frame members, and propelling means partially housed within said fins. 9. In a dirigible balloon, an aerostat comprising a rigid tractor head, aerial propelling means carried thereby, and interchangeable flexible load sections trailing behind and flexibly tied to the head section. 10. In a dirigible balloon, an aerostat comprising a rigid tractor head, aerial propelling means carried thereby, steering means also carried by said head, and interchangeable flexible load sections trailing behind and flexibly tied to the head section. 11. In a dirigible balloon, an aerostat comprising a rigid tractor head, aerial propelling means carried thereby, interchangeable flexible load sections trailing behind and flexibly tied to the head sections, and streamlining flaps flexibly connecting said sections at the periphery of the aerostat. 12. In a dirigible balloon, an aerostat comprising a rigid head section, flexible load sections trailing behind and flexibly tied to the head section, and a car supported under the aerostat and embodying separable sections supported by respective sections of the aerostat. 13. In a dirigible balloon, an aerostat comprising a rigid head section, flexible load sections trailing behind and flexibly tied to the head section, and a car supported under the aerostat and embodying sections supported by respective sections of the aerostat, said car sections being placed in communication by flexible tubular vestibules. 14. In a dirigible balloon, an aerostat comprising a rigid head section, flexible load sections trailing behind and flexibly tied to the head section, and a car supported under the aerostat and embodying sections supported by respective sections of the aerostat, and having tubular inflated jackets. 15. In a dirigible balloon, an aerostat comprising a rigid head section, flexible load sections trailing behind and flexibly tied to the head section, and a car supported under the aerostat and embodying sections supported by respective sections of the aerostat, and having tubular inflated jackets, and pressure tight vestibules flexibly connecting the car sections. 16. In a dirigible balloon, an aerostat comprising a rigid head section, flexible load sections trailing behind and flexibly tied to the head section, a non-rigid tail section, a car supported under the aerostat and embodying sections flexibly connected by vestibules, a framework connecting the rear ends of the car and aerostat, and vertical and horizontal stabilizers mounted on said framework. 17. In a dirigible balloon, a rigid head section, a sustaining gas container therein and a non-rigid load section trailing behind and attached to said head section. 18. In a dirigible balloon, a rigid head section, a sustaining gas container therein, a non-rigid load section trailing behind and attached to said head section, and a pro-

- pellet unit supported directly on said rigid head section.
19. A dirigible balloon, a rigid head section, a sustaining gas container therein, a non-rigid head section trailing behind and attached to said head section, steering vanes attached directly to said head section for guiding said balloon.
20. In a dirigible balloon, a rigid head section, a sustaining gas container therein, a non-rigid load section trailing behind and attached to said head section, a propelling unit supported on said head section and steering vanes attached directly to said head section.
21. In a dirigible balloon, an aerostat comprising a rigid head section and a plurality of flexible load sections trailing behind and each attached directly to said rigid head section.
22. In a dirigible balloon, an aerostat comprising a rigid head section and a plurality of flexible load sections trailing behind and attached to said head section, said sections having conical interfitting ends.
23. In a dirigible balloon, a load section having a substantially conical end adapted to interfit with another section.
24. In a dirigible balloon, a load section adapted to interfit with other sections having a substantially conical projection at one end and a substantially conical depression at the other end adapted to fit adjacent sections.
25. In a dirigible balloon, an aerostat comprising a plurality of separable load sections and an individual load-carrying car for each section.
26. In a dirigible balloon, a load section provided with an axial tubular opening and means extending therethrough for attaching said section to an adjacent section.
27. In a dirigible balloon, a load section provided with a peripheral flap to cover junctures with an adjacent section, said load section having a substantially conical end to interfit with an end on an adjacent section.
28. In a dirigible balloon, a head section, a plurality of load sections, and a tail section and an individual car attached to each section.
29. In a dirigible balloon, cars carried by said balloon, and flexible air-tight passages between cars.
30. In a dirigible balloon, an aerostat, diagonally stabilizing fins fixed thereon, and propelling means partly housed within said fins.
31. In a dirigible balloon, separable aerostat sections, and tension cables for interconnecting said separable sections.
32. In a dirigible balloon, separable aerostat sections and axially extending central tension cables for interconnecting said sections and the front section.
33. In a dirigible balloon, an aerostat comprising a rigid head section having box girder longérons, and also having internal transverse frame members united to said longérons, stream-lined stabilizing fins projecting outward from the head section and anchored to said members, and propelling means partially housed within said fins.
34. In a dirigible balloon, an aerostat comprising a rigid head section having longérons, and also having internal transverse frame members united to said longérons, interchangeable flexible load sections trailing behind the head section and flexibly tied thereto, streamlined stabilizing fins projecting outward from the head section and anchored to said frame members, and propelling means partially housed within said fins.

In testimony whereof I affix my signature.

FRANK SHORT.
